CLAIM

The ornamental design for a perforated card, as shown and described.

DESCRIPTION

FIG. 1 is a perspective view of a perforated card showing the claimed design;

FIG. 2 is a front view thereof;

FIG. 3 is a rear view thereof;

FIG. 4 is a lengthwise side view thereof; and,

FIG. 5 is a widthwise side view thereof.

The outer rings of the perforations of the perforated card shown in FIGS. 1-3 show curvature of the perforations and are included in the claimed design.

The broken lines in FIGS. 1-5 forming other elements of a perforated card illustrate environmental subject matter that forms no part of the claimed design.
